UNITED STATES PATENT OFFICE.

CLARENCE W. UUTZMAN, OF CHICAGO, ILLINOIS, ASSIGNOR TO UNITED STATES GYPSUM COMPANY, OF CHICAGO, ILLINOIS, A CORPORATION OF NEW JERSEY.

FLOOR CONSTRUCTION.

1,312,287.

Specification of Letters Patent.

Patented Aug. 5, 1919.

Application filed August 30, 1915. Serial No. 47,968.

To all whom it may concern:

Be it known that I, CLARENCE W. UUTZMAN, a citizen of the United States, residing at Chicago, in the county of Cook and State of Illinois, have invented certain new and useful Improvements in Floor Constructions, of which the following is a specification.

This invention relates in general to building constructions, and more particularly to the floor structure which in modern fire-proof buildings is made of concrete or stucco poured over forms supported upon temporary false work, so that the floor structure 10 and girders or supporting beams are formed integrally of the concrete or stucco.

The forms which have been used prior to my invention have either been of built-up wooden construction which must be assembled on each job and taken down after the concrete or stucco has set, or of substantially inverted U-shape with horizontally projecting flanges at their ends. The inverted U-shape forms were supported upon 20 the false work with the flanged ends of adjacent forms in contiguous relation to produce the beams between the sides of adjacent forms when concrete was poured over them. Unless the forms are laid with extreme accuracy the beams produced thereby 25 will be irregular in width, and furthermore, when concrete is poured to form one beam the forms have a tendency to separate at their sides under the weight of the concrete, and in many instances the forms will be 30 distorted at their line of curvature between the vertical side walls and the horizontal top walls. A further disadvantage of forms of this character is that they can only be 35 laid to produce beams extending in one direction, whereas it is often desirable to have the integral beams extend in both directions, that is, both laterally and longitudinally of 40 the floor structure.

My present invention is designed to overcome the weaknesses and objectionable features of the forms heretofore employed in producing concrete floors and contemplates the provision of a construction which will 45 permit the accurate and uniform formation of both transverse and longitudinal beams in the floor and which will maintain its shape, not be subject to displacement or distortion under the weight of the concrete 50

when poured and which will become anchored to the concrete and form a permanent part of the floor structure.

With these and other objects in view my invention contemplates the use of channel-shaped molds which may be arranged upon 55 temporary false work in the position where the beams and cross beams are to be formed, these molds being of a predetermined width and of sufficient strength to maintain their original shape when the concrete or stucco 60 is poured into them.

Another object of my invention is to provide supporting means for the concrete poured between the various channel members, said supporting means being constructed to rest upon the upper edges of the channel members and completely cover the 65 spaces between adjacent members.

A further object of my invention is to provide means for fastening the ceiling 70 boards, to which the plaster of the underlying ceiling is applied, to the concrete beams so that the boards may be attached and secured in place without boring or 75 plugging into the concrete or stucco.

For the purpose of facilitating an understanding of my invention I have disclosed preferred embodiments thereof in the accompanying drawings, to which reference is made in the following description. Referring to the drawings—

Figure 1 is a fragmentary sectional view of a floor construction embodying my invention;

Fig. 2 is a similar view showing a slightly 90 different form;

Fig. 3 is a similar view showing another form of anchor;

Fig. 4 is a sectional view on the line 4—4 of Fig. 2; and,

Fig. 5 is a fragmentary perspective view showing the manner of joining intersecting channel members.

Referring to the drawings, and more particularly to Figs. 1 to 3 thereof, it will be observed that in lieu of providing a channel for the concrete beams 6 by means of inverted forms having horizontal flanges which abut beneath and along the center line of each beam, I employ channel-shaped 100 members designated by reference character 7 in Fig. 1 and by reference character 8 in Figs. 2 and 3, which are molded out of

suitable plastic material such as stucco having paper incorporated in its construction. These channel-shaped members are substantially U-shape in cross section and may be 5 made in any size of beam cross section and length desired, and are capable of being sawed or cut to fit into any place where they may be desired. In forming the floor structure these channel members are positioned upon temporary false work and supported thereby in the positions where the floor supporting beams are to come. In case 10 a two-way construction is desired, that is, one in which the beams will run both longitudinally and transversely of the floor structure, the channel members are arranged in the desired relation. Where they join 15 or intersect the side walls may be cut out to receive the ends of the abutting section, as shown in Fig. 5, in which reference character 9 indicates where portions have been cut out of the side walls of the members 7. In making a joint the ends of the channels are preferably chamfered off as shown to 20 make a close strong union, and the joint is secured together by metal clips 11 bent to embrace both of the intersecting channel members. A corner joint is indicated by reference character 12, the construction of 25 which will be obvious. It will thus be manifest, particularly from Fig. 5, that when the channel members are properly joined and positioned they produce a continuous channel into which concrete or 30 other material may be poured to form integrally united beams. In Fig. 5 I have illustrated a construction which provides for T-joints, cross-joints and L-joints.

Referring again to Fig. 1, after the channel members have been positioned as described 40 the space between members is covered by sheets of plaster board 13, or other material which will form a permanent part of the floor structure. Metal 45 clips 14, shaped substantially as shown, unite the upper edges of the channel members with the sheets 13. The reinforcing members 15 with which the girders are customarily equipped and which may be of any 50 preferred type, are now positioned in the channel members whereupon concrete or other plastic material is poured over the entire form produced by the channel members and the covering sheets. The concrete 55 will fill the channel members producing the beams and will flow over the covering sheets producing the floor proper which, as will be obvious, is integrally connected with the beams. A finishing surface 16, of any preferred 60 type, may then be applied to the concrete. Since the bottom and side walls of the channel members are of integral construction and since the upper edges of the channel members are braced and supported 65 against lateral displacement by the sheets

13 it will be obvious that a very strong mold is produced in which beams of exactly the desired dimensions will be formed.

The channel members are thickened at the lower corners between the upright and bottom walls so that they are strongest at this point where the ordinary forms are usually weakest, and any liability of distortion of the forms by the weight of the poured concrete or other material is thereby eliminated. 70

In the construction shown in Fig. 1, I attach to the sides of the channel members 7 adjacent their lower corners, metal brackets 17 which are secured to the channel members by nails 18 before the concrete 80 is poured, the nails being preferably of sufficient length to extend into the concrete or other material and be anchored therein when the beam is formed. These brackets are adapted to support ceiling boards 19, 85 preferably of plaster board, which may be anchored in position by nails 21. The plaster 22 of the underlying ceiling may then be applied to the boards and the bottoms of the channel members 7, producing 90 a finished ceiling underneath.

In Fig. 2 I have shown another form of the invention in which the channel members 8 are slightly shallower than the channel members 7 shown in Fig. 1. Instead of employing sheets of plaster board 13 as in the form shown in Fig. 1 I employ covering slabs or plates 23 formed of corrugated metal or the like, bent as shown to provide a thickened portion 24 at the juncture of the beam with the floor slab. This figure shows the lower edges of the plates as provided with one form of spaced clips or fingers 25 and 26 which embrace opposite sides of the upper edges of the channel members and securely lock the plates 23 to the channel members. The plates are therefore supported by and securely attached to the spaced channel members to provide a rigid mold for the concrete or stucco. When the construction 100 embodies a two-way structure, as shown in Fig. 5, the plates 23 are shaped to cover an opening bounded by four of the channel members, and each of the four edges of the plate is provided with the holding fingers 105 25 and 26.

In this form of the invention I provide the channel members 8 with fastening devices 27 which are inserted through slits in the bottom wall in the channel member and 110 are provided at their upper ends with anchors 28 shaped as shown in Fig. 2. The fastening devices are provided near their upper ends with openings or depressions and the anchors are provided with correspondingly positioned inwardly projecting extensions which enter the openings and securely lock the anchors to the fastening devices. When the beam is poured the fastening devices are securely anchored in the concrete. 115 130

The lower ends of the fastening devices are shaped substantially as shown to provide slots 29, the lower wall of the channel member being provided with depressions 31 to receive the metal which forms the slots. Substantially U-shaped clips 32 are inserted into the slots 29 and the plaster block or other ceiling blocks 33 are provided with slots 34 at their ends adapted to receive the lower horizontally projecting portions of the clips by which the blocks are supported in position. The fastening devices 27 are positioned before the concrete is poured, as previously explained, and after the false work has been taken down the plaster blocks may be secured in position by means of the clips 32 as will be readily understood.

In Fig. 3 I have illustrated a slightly modified construction in which the anchor 20 consists of a nail or spike 35 inserted through apertures in the upper end of the fastening device 27. The clips 36 in this instance are of sufficient length to embrace the slabs of plaster board 37 instead of being inserted in slots in the end thereof as it is disclosed in Fig. 2. With either form of the invention the plaster board or other ceiling material may be readily secured in position after the false work or centering has been taken down.

From the foregoing it should be apparent that I have provided a floor construction which is strong and rigid, which will insure that the beams will be of the required dimensions so that the exact amount of concrete or other material necessary can be accurately figured in advance, and which pro-

vides means for quickly and easily attaching the ceiling boards to the beams without boring or plugging into the concrete. If it should be desirable to employ metal or other 40 lath in lieu of the plaster board for ceiling purposes a slightly different type of clip would be used for attaching the metal lath to the beams. While I have shown and described practical and preferred embodiments 45 of my invention it should be manifest that numerous minor variations in the size, shape, proportions and arrangements of the various parts may be resorted to without departing from the scope of the invention as 50 defined in the following claim.

I claim:

A floor construction, comprising a plurality of channel-shaped members extending in two directions throughout the floor area, 55 said members being securely fastened together at their points of intersection so as to produce continuous and intersecting channels, means for covering the spaces between said members, plastic material disposed over 60 said covering means and filling said channel members to produce a continuous floor structure having integral beams extending longitudinally and transversely in the floor, fastening devices carried by said channel 65 members, ceiling boards or blocks disposed beneath the members, and clips detachably engageable with said fastening devices for holding said ceiling boards or blocks in position.

CLARENCE W. UTZMAN.
